(57) **CLAIM**

The ornamental design for a fastening system for flexible material, as shown and described.

DESCRIPTION

FIG. 1 is an exploded front elevational view showing my new design for a fastening system for flexible material; FIG. 2 is a rear elevational view;

FIG. 3 is an exploded front perspective view;

FIG. 4 is a front perspective view;

FIG. 5 is an exploded left side elevational view which is a mirror image of the right side exploded view;

FIG. 6 is a left side elevational view; which is a mirror image of the right side elevational view;

FIG. 7 is a bottom plan view; and,

FIG. 8 is a top plan view.

1 Claim, 3 Drawing Sheets(56)
